DESIGN FOR A ROOF VENTILATOR

Arthur E. Waterman and Frederick J. Kreutzer,
Fort Atkinson, Wis.

Application July 5, 1940, Serial No. 93,436

Term of patent 14 years

To all whom it may concern:

Be it known that we, Arthur E. Waterman and Frederick J. Kreutzer, citizens of the United States, residing at Fort Atkinson, in the county of Jefferson and State of Wisconsin, have invented a new, original, and ornamental Design for Roof Ventilators, of which the following is a specification, reference being had to the accompanying drawing, forming a part thereof.

Fig. 1 is a bottom perspective view of a roof ventilator showing our new design.

Fig. 2 is a top plan view of our design.

The sides not shown are similar to the sides shown.

We claim:

The ornamental design for a roof ventilator, as shown and described.

ARTHUR E. WATERMAN.
FREDERICK J. KREUTZER.
